UNITED STATES PATENT OFFICE.

JOHN E. MITCHELL, OF ST. LOUIS, MISSOURI.

COTTON GIN.

Application filed August 8, 1927. Serial No. 211,317.

The general object of this invention is to provide an improved cotton gin in which provision is made for the more effective cleaning of the cotton and with less waste 5 thereof, than is possible with the type of gin now commonly employed.

My improved gin embodies in its construction many of the essential elements of the modern huller gin of either the single or 10 double rib type. Such gin consists, essentially, of circular saws spaced apart and projecting through spaces between either one or two sets of stationary ribs, according to the type of machine. In the double rib type 15 of machine, one set of these ribs, known as the "huller ribs", is located near the peripheries of the saws and extends downwardly from the front of the roll box. The second set of ribs, known as "ginning ribs", is located nearer the center of the saws and extends from the rear of the roll box through the spaces between the saws and down past the bottoms of the saws. The huller ribs are spaced sufficiently wide apart to permit 25 the passage of cotton seeds between them, but the width of these spaces is such as to prevent the passage through them of hulls carried up with the cotton by the saws. The ginning ribs are located in relatively close 30 proximity to the sides of the respective saws to prevent the passage of seeds through the spaces between them. In practice, the huller ribs separate the major portion of the hulls and trash from the cotton, such hulls falling 35 out of the machine, while the ginning ribs operate to separate the seeds from the cotton, which seeds travel downward over the surfaces of the ribs and fall out of the machine.

In the single rib type of huller gin, one 40 set of ribs only is employed and each of these ribs is provided with a huller member projecting out beyond the periphery of the gin saws, the ribs proper operating to separate the seed from the cotton, and the huller members, to separate the hulls and trash from the cotton. With the double rib gin, the hulls are discharged separately from the seeds, while in the single rib huller gin, the hulls and seeds are discharged together.

50 In front of the ginning saws and extending the entire length of the saw cylinder, the gins of either of the types referred to have a spiked roller known as a "picker roller", which rotates clockwise, or toward the 55 saws.

While my improved gin would preferably embody in its construction the single set of huller ribs above referred to, it may equally well embody both huller ribs and ginning ribs in its construction. In the latter case, however, only the huller ribs would enter 60 the operative combination of parts constituting my invention.

In the interest of brevity of description, I will hereinafter use the term "huller ribs" 65 as referring to the outer set of ribs where two sets of ribs are employed, or to the single set of ribs with huller members thereon where only one set of ribs is employed.

In operation, the cotton (or, if it has not been thoroughly cleaned, the cotton mixed with the hulls and trash) is fed into the breast of the gin where it falls down through the space between the roll box and the outer housing onto the picker roller referred to. 70 This roller throws the cotton against the teeth of the ginning saws, which carry it up and through the spaces between the huller ribs. These strip off most of the hulls, sticks, stems, etc. which may be mixed with 75 the cotton. The hulls and trash separated in this manner fall down on the spikes of the picker roller. If these hulls are not too large, or the amount too great, they can be discharged by the picker roller from the machine through the opening at the bottom of the breast of the gin without the necessity of having to resort to what is known in the trade as "dumping the breast of the gin".

If the hulls are too large, however, or the 80 percentage of hulls and trash too great, they accumulate in the working space above the picker roller to such an extent that it is necessary to occasionally shut off the feed and discharge the accumulation. This not 85 only causes loss of time in ginning, and the waste of a great deal of cotton, dumped out with the hulls, but the accumulation of hulls and other foreign matter in the working space above the picker roller results in the 90 sharp teeth of the gin saws constantly cutting or chipping pieces of the hulls and sticks and carrying the same along with the cotton into the roll box, whereby the grade 95 of the cotton is materially lowered owing to 100 the admixture therewith of these small particles of foreign matter.

These picker rollers, however, are universally used in huller gins and are adjustable to and from the gin saws, so as to in- 105 110

crease or decrease the space between the teeth of the gin saws and the ends of the spikes of the picker roller. The purpose of this adjustment is to enable the ginner to back the picker roller away from the gin saws to permit discharging more freely the hulls and trash when there is an excessive amount to deal with. Such adjustment presents the difficulty, however, that when the picker roller is backed out far enough to permit the free discharge of a large amount of the hulls and trash, it inevitably permits also the discharge of a considerable amount of cotton along with the hulls; while, on the other hand, if the picker roller is set up close enough to the ginning saws to avoid such waste of cotton, the hulls and trash are not discharged rapidly enough, and hence accumulate in the space above the picker roller, necessitating the occasional dumping of the breast above referred to.

In addition to the impossibility of securing an ideal adjustment of the picker roller relative to the gin saws, another disadvantage inherent in the use of the picker roller is, that as the spikes rotate in a direction toward the teeth of the gin saws, considerable chipping, cutting or barking of hulls and stems results from the latter being forced or crowded by the spikes against the teeth of the saws, even when the percentage of such hulls and trash is not large.

In order to avoid the difficulties attending the use of a picker roller, and at the same time to provide means for effectively separating the hulls and trash from the cotton and continuously removing the latter from the breast, or working chamber, of the gin, with a minimum waste of cotton, I dispense entirely with the use of the picker roller in my improved gin and substitute for the same certain elements of the cotton cleaning and reclaiming machine described and illustrated in my prior patent No. 1,613,242, dated January 4th, 1927, and notably, the reclaiming saw cylinder.

In my present invention, I accomplish practically the same results in the use of reclaiming saws in connection with the modern cotton gin as characterized the use of the cotton cleaning machine of my patent referred to, the principal differences being in the means employed for delivering the cotton and hulls to the ginning saws and in the use of the stationary huller ribs, in connection with the ginning saws, for separating the hulls and trash from the cotton, instead of the kicker roll of said cotton cleaning machine.

In the accompanying drawing—

The figure is a cross-sectional view of a gin constructed according to my invention and illustrating the essential elements of the latter, the gin shown being of the double rib type.

Referring now to the drawing, the numeral 1 indicates the casing of a gin, in which casing is provided a roll box 2 and a breast, or working chamber, 3 formed by one wall 4 of the roll box and the front wall 5 of the casing. Depending from the rear side of the roll box 2 is a series of ginning ribs 6, and depending from the front wall of the roll box is a series of huller ribs 7. Mounted in suitable bearings in the end walls of the casing 1 is a gin saw cylinder, one of the saws thereof being indicated at 8. The above parts are of ordinary construction and are practically standard in the modern type of double rib gin. To make the present invention clear, it may be further stated, however, that the huller ribs 7 are spaced at a sufficiently wide distance apart to permit the seeds to be drawn through the spaces between them by the gin saws while, at the same time, such spaces are narrow enough to preclude the passage of hulls, trash, and the like, which latter are thereby separated from the cotton as the latter is drawn through the spaces between the huller ribs by the saws, and are removed from the gin in a manner to be presently described. The ginning ribs 6 extend through the spaces between the saws and are located practically at the bottom of said spaces. Each pair of ribs is positioned in close proximity to the sides of one of the gin saws so as to prevent the seeds from being drawn through the spaces between these ribs as the cotton is carried through by the saws. As they are separated from the cotton, the seeds slide down the outer or front face of the ribs 6 and fall out of the machine.

My invention consists, essentially, in combining with the construction of a single or double rib huller gin, novel means for delivering the mixed cotton and hulls to the gin saws and novel means co-operating with the gin saws for continuously removing the hulls and trash separated from the cotton by the huller ribs from the gin, and novel means for permitting such continuous removal of the hulls and trash with a minimum waste of cotton in the operation.

To this end, I provide at the bottom of the breast 3 a rotatable member 9, the purpose of which is to deliver the mixed cotton and hulls to the gin saws. This member, in its preferred form, comprises a cylinder having a series of angle bars or ribs 10 secured about its periphery at suitable distances apart and extending longitudinally of the cylinder. This member may be termed a feed roll. Below the feed roll 9, I rotatably mount in the end walls of the casing 1 a reclaiming saw cylinder 11 which, as in the case of the gin saw cylinder, comprises a series of circular saws suitably spaced apart throughout the length of the cylinder. The reclaiming saw cylinder, however, is of much

less diameter than the gin saw cylinder. The gin saw cylinder may be rotated in any suitable way, as by means of a pulley 12 mounted on its shaft and driven by a belt (not shown) in the usual way. The feed roll 9 and the reclaiming saw cylinder 11 are driven from the shaft of the gin saw cylinder by conventional driving mechanism (not shown), which driving mechanism is 5 preferably arranged to drive the feed roll in the same direction as the gin saw cylinder, but in all cases, the reclaiming saw cylinder 11 is driven in a direction opposite to that of the gin saw cylinder. In other words, 10 the gin saws are rotated in a clockwise direction and the reclaiming saws, in an anti-clockwise direction. The respective directions of rotation of these parts is indicated by the arrows on the drawing. The reclaiming saws have two functions; one, to remove the hulls and trash from the space immediately above them, constituting, in effect, the working chamber of the gin, and the other to deliver cotton carried out of the working 15 chamber to the gin saws 8. To facilitate the performance of these dual functions without the loss of cotton, I associate with the reclaiming saw cylinder, yielding means, the function of which is to cause the cotton to 20 adhere to the teeth of the reclaiming saws while permitting the hulls and trash to be carried beyond said yielding means and thrown out of the machine by the reclaiming saws. Such yielding means find their 25 preferred embodiment in a series of brushes 13 mounted at suitable intervals throughout the length of a bar 14 extending inwardly and downwardly from the bottom of the front wall 5 of the casing 1. The brushes 13, or 30 other yielding means, have their outer ends located in close proximity to the teeth of the reclaiming saw cylinder so that, in the rotation of said cylinder, cotton carried around by the saws, which will usually be in the 35 form of small locks, will be caused to adhere to the teeth of the reclaiming saws as they pass under the yielding means or brushes 13, while the pliability of such brushes or yielding means is such as to permit the hulls and 40 trash to pass under them without being forced into engagement with the teeth of the reclaiming saws. Hence, such hulls and trash will be continuously discharged by the reclaiming saws at a point beyond the yielding 45 means 13. To prevent the tendency of the cotton passing beyond the yielding means 13 to be thrown by centrifugal force from the reclaiming saws, I preferably locate an angle bar 15 below the reclaiming saws, to 50 extend throughout the length of the cylinder formed thereby, which bar is so positioned that it will tend to prevent any outward throw of the cotton from the teeth of the reclaiming saw cylinder. 55

60 In operation, the mixed cotton and hulls

are fed into the space between the roll box and outer housing of the gin stand, where it falls into contact with and is engaged by the rotating feed roll 9. This feed roll can be so mounted and housed as to permit rotating it in the opposite direction from that shown by the arrow, to cause the lower portion of it to throw the cotton from the bottom over onto the ginning saws above the reclaiming saws. I prefer, however, to rotate it in the direction shown. In either event, the cotton mixed with hulls is thrown by the feed roll into contact with the portion of the ginning saws extending through the spaces between the huller ribs 7 and is instantly engaged by the teeth of the ginning saws and carried up through the spaces between these ribs, the spaces between them being narrow enough to prevent the hulls, stems and other extraneous matter from going through with the cotton and seeds. 70

The hulls and stems separated by the huller ribs 7 from the cotton fall down through the space between the ginning saws and the beaters 10 on the feed roll 9 onto the reclaiming saw cylinder 11. Since the upper half of the reclaiming saw cylinder is rotating away from the ginning saws, it is obvious that none of the hulls and trash can be again forced back into contact with the rapidly moving teeth of the ginning saws, as occurs in the operation of the picker rollers universally employed in all other huller gins. 80

Any small locks of cotton which might 100 not be firmly engaged by the teeth of the ginning saws and which become mixed with the hulls, stems, and other trash separated by the huller ribs, fall onto the reclaiming saw cylinder and are carried by the same 105 around to the brush or yielding member 13, which causes such locks of cotton to be firmly engaged by the teeth of the reclaiming saws and to be carried around near enough to the teeth of the ginning saws so that the latter, which move at a much greater rate of speed than the teeth of the reclaiming saws, will doff or remove all cotton adhering to the teeth of the latter. The reclaiming saws may be in the same plane with 110 the ginning saws, or, if preferred, they may alternate in position with the ginning saws and project into the spaces between the latter. The important point of this arrangement is that the teeth of the reclaiming saws shall at all times rotate in such proximity to the teeth of the ginning saws that the latter will readily doff or remove the cotton from the former. The exact diameter of 115 the reclaiming saws relative to the ginning saws is not important, although in all cases the reclaiming saws will have, as stated above, a much less diameter than that of the ginning saws. It is also important that 120 the reclaiming saw cylinder shall have a 125 130

surface speed of rotation considerably less than that of the ginning saw cylinder and shall rotate in a direction opposite to that of the ginning saw cylinder.

5 It will be readily seen that my arrangement differs from the ordinary huller gin, first, in the substitution of a reclaiming saw cylinder rotating, as to its upper half, in a direction away from the gin saws, for the picker roller rotating, as to its upper half, 10 in a direction toward the gin saws; second, in the interposition of a rotary member, the feed roll 9, between the bottom of the breast 3 and the reclaiming saw cylinder for causing 15 the mixed cotton and hulls to be thrown against the gin saws at a point above the reclaiming saw cylinder, whereas in the ordinary huller gin, the cotton and hulls fall down directly upon the picker roller; and, 20 third, in the provision of the yielding member or brush 13 for causing small locks of cotton, not engaged by the teeth of the gin saws, to be engaged by the teeth of the reclaiming saws and thereafter delivered by 25 the reclaiming saws to the gin saws. It will also be seen, as compared with the cotton cleaning machine of my patent above referred to, that I utilize the stationary huller ribs 7 of the ordinary cotton gin for preventing 30 the hulls and trash from being carried around by the gin saws, in place of the rotatable kicker roll 2 of said patent. Further, that in place of the hull-board 3 of the machine of said patent for causing the mixed 35 cotton and hulls to move into contact with the saw cylinder, I employ the rotatable member 9 having beaters 10, which acts to positively throw the cotton and hulls against the teeth of the gin saws.

40 In order that the advantages of my improved gin may be better understood, it should be explained that in former times, the cotton delivered for ginning was usually much cleaner than obtains at the present 45 time, owing to the fact that the cotton was all hand-picked, and practically only the cotton was pulled from the plant. In more recent years, with the advent and general use of the cotton cleaning machine, the pickers 50 will strip the bolls from the plant with the cotton, and all modern gins are equipped with cotton cleaning machines ahead of the gin to separate the bolls and trash from the cotton before the cotton is ginned. Still 55 more recently, in certain sections, cotton is stripped from the plant by means of crude machines drawn over the ground, and such cotton, owing to the admixture therewith of a large portion of branches, twigs, hulls, and 60 the like, is difficult to clean thoroughly and the ginning of the cotton is still more difficult. In fact, in some cases, the cotton delivered to the gin contains almost as great an admixture of hulls and trash as formerly obtained with cotton delivered to the

cotton cleaning machine ahead of the gin. The advantages in the use of my improved gin, therefore, are far more pronounced where there is a relatively large percentage of hulls and trash contained in the cotton 70 delivered to the breast of the gin, than where the cotton is relatively free from such admixture, as would be the case, for example, where a cotton cleaning machine of the type disclosed in my patent above referred to is 75 used ahead of the gin. Under all circumstances, however, my improved gin possesses distinct advantages in operation over the present type of huller gin employing a picker roller, owing to the fact that whether the 80 portion of hulls and trash mixed with the cotton be great or small, the reclaiming saw continuously removes such hulls and trash from the gin saws and minimizes the barking and cutting thereof by the gin saws. At 85 the same time, as above explained, all tendency of hulls and trash to accumulate in the space above the reclaiming saws is prevented by reason of the fact that the hulls and trash are continuously carried out of 90 the breast by the reclaiming saws, and this is effected with practically no waste whatever of cotton. It will be observed that the reclaiming saw cylinder has one portion operating in the clear with respect to the space 95 adjacent the gin saws, and hence that the removal and discharge of the hulls and trash from the working chamber of the gin is continuously and rapidly performed.

100 I claim:

1. A cotton gin comprising, in combination with rotatable gin saws and stationary huller ribs through spaces between which latter a portion of the gin saws project, a rotatable member for feeding the raw cotton 105 to the gin saws, and means for continuously removing hulls and trash, separated from the cotton by the co-action of the gin saws and huller ribs, and immediately and directly discharging same out of the machine comprising a reclaiming saw cylinder mounted to 110 rotate in co-operative relation with, but in a direction opposite to that of said gin saws, the construction providing an uninterrupted space between said member and the reclaiming saw cylinder.

115 2. A cotton gin comprising, in combination with rotatable gin saws and stationary huller ribs through spaces between which latter a portion of the gin saws project, a rotatable member for feeding the raw cotton 120 to the gin saws, and means located below said feeding means for continuously removing hulls and trash, separated from the cotton by the co-action of the gin saws and huller ribs, and discharging same out of the machine comprising a reclaiming saw cylinder mounted to rotate in co-operative relation with, but in a direction opposite to 125 that of said gin saws, and having a portion 130

operating in the clear, the construction providing an uninterrupted space between said member and the reclaiming saw cylinder.

3. A cotton gin comprising, in combination with rotatable gin saws and stationary huller ribs through spaces between which latter a portion of the gin saws project, a rotatable member for feeding the raw cotton to the gin saws, and a reclaiming saw cylinder for continuously removing hulls and trash, separated from the cotton by the co-action of the gin saws and huller ribs, and immediately and directly discharging same out of the machine and simultaneously returning cotton removed with such hulls and trash to a position to be engaged by the teeth of said gin saws, the construction providing an uninterrupted space between said member and the reclaiming saw cylinder.
4. A cotton gin comprising, in combination with rotatable gin saws and stationary huller ribs through spaces between which latter a portion of the gin saws project, a rotatable member for feeding the raw cotton to the gin saws, and means for continuously removing hulls and trash, separated from the cotton by the co-action of the gin saws and huller ribs, and immediately and directly discharging same out of the machine and simultaneously returning cotton removed with such hulls and trash to a position to be engaged by the teeth of the gin saws comprising a reclaiming saw cylinder mounted to rotate in a direction opposite to that of said gin saws and with the teeth of its saws located in close proximity to the teeth of the respective gin saws, and a yielding member located in proximity to the surface of said reclaiming saw cylinder for causing cotton carried under said yielding member by said saw-cylinder to adhere to the teeth of the saws thereof, the construction providing an uninterrupted space between said member and the reclaiming saw cylinder.

located in close proximity to the teeth of the respective gin saws, the construction providing an uninterrupted space between said member and the reclaiming saw cylinder.

5. A cotton gin comprising, in combination with rotatable gin saws and stationary huller ribs through spaces between which latter a portion of the gin saws project, rotatable means located below the breast of the gin for delivering raw cotton fed into the breast to the surface of the gin saws, means for continuously removing hulls and trash, separated from the cotton by the co-action of said gin saws and huller ribs, and immediately and directly discharging same out of the machine and simultaneously returning cotton removed with the hulls and trash to a position to be engaged by the teeth of the gin saws, comprising a reclaiming saw cylinder mounted to rotate in a direction opposite to that of said gin saws and with the teeth of its saws located in close proximity to the teeth of the respective gin saws, and a yielding member located in proximity to the surface of said reclaiming saw cylinder for causing cotton carried under said yielding member by said saw-cylinder to adhere to the teeth of the saws thereof, the construction providing an uninterrupted space between said member and the reclaiming saw cylinder.

In testimony whereof, I have hereunto set my hand.

JOHN E. MITCHELL.
